UNITED STATES PATENT OFFICE.

ERNEST W. STAMM, OF ST. LOUIS, MISSOURI.

BOX-FASTENER.

1,080,859.

Specification of Letters Patent.

Patented Dec. 9, 1913.

Application filed May 7, 1912. Serial No. 695,645.

To all whom it may concern:

Be it known that I, ERNEST W. STAMM, a citizen of the United States, residing at St. Louis, Missouri, have invented a certain new and useful Improvement in Box-Fasteners, of which the following is a full, clear, and exact description, such as will enable others skilled in the art to which it appertains to make and use the same.

10 This invention relates to box fasteners of the type which comprise coöperating members arranged on the inside of the box and a seal which has to be broken before said members can be actuated to release the lid or 15 cover of the box.

One object of my invention is to provide a box fastener of the character described that comprises only a few members of simple construction that can be manufactured 20 cheaply.

Another object is to provide a box fastener of the character described which is so designed that the act of breaking the seal, disengaging the movable part or element of 25 the device, and grasping the lid or cover of the box is effected by practically a single operation.

Other objects and desirable features of my invention will be hereinafter pointed out.

30 Figure 1 of the drawings is a vertical sectional view of a box or shipping case provided with a fastener or lid-locking device constructed in accordance with my invention; Fig. 2 is a similar view showing 35 how the movable part or element of the device is disengaged so as to release the lid or cover of the box; Fig. 3 is a vertical sectional view taken on approximately the line 3—3 of Fig. 1 looking in the direction indicated by the arrow; and Fig. 4 is a top plan view of a portion of the cover of the box.

Referring to the drawings which illustrate the preferred form of my invention, A designates the movable lid or cover of a 45 box or shipping case, and B designates the front wall of the box. Coöperating members are arranged on the inside of the box for locking the lid A in its closed position, and an opening 1 is formed in said lid so as to 50 permit the coöperating parts of the device to be disengaged so as to release the lid A. A seal C, which preferably consists of a piece of card-board or some other suitable material, is arranged on the inside of the 55 lid A over the opening 1 so as to prevent

the lid from being released and raised without first breaking the seal.

In the embodiment of my invention herein shown, the movable element of the locking device consists of a resilient member 2 preferably formed from a strip of spring metal or material that has some resiliency. Said member 2 is secured to the inner face of the front wall B of the box, and it is bent inwardly or offset at 3, as shown in 60 Figs. 1 and 2, so that the upper portion of same will be spaced away slightly from the inner side of the front wall B of the box. At the upper end of the member 2 is a laterally projecting lip or extension 4 which engages a member 5 on the under side of the lid A when the lid is closed and thus securely locks said lid in its closed position. A pocket 6 or holder is provided on the under side of the lid A to receive the seal 70 C and hold said seal in operative position with relation to the hole 1 in the lid A, and in the preferred form of my invention as herein shown, the member 5 that coöperates with the movable member 2 of the device is 75 formed integral with the pocket or seal-holder 6, said pocket 6 having an opening 6^a that aligns with the opening 1 in the lid A of the box. The pocket 6 is provided with laterally projecting flanges 7 through 80 which fastening devices 8 pass, as shown in Fig. 3, so as to secure said pocket to the under side of the lid A, and said pocket is open in its front end, as shown in Figs. 1 and 2, so as to permit the seal C to be introduced into same. The side and rear walls of the pocket 6 prevent the seal from being shifted or moved out of alignment with the opening 1 in the lid of the box, and said pocket is arranged close enough to the front 85 wall B of the box to prevent the seal from being moved forwardly far enough to uncover the opening 1 in the lid or shift the seal out of alignment with said opening. It will, of course, be understood that it is 90 immaterial so far as my broad idea is concerned whether the member 4 is formed integral with the pocket 6 or from a separate piece of material but I prefer the construction herein shown on account of its simplicity, durability and low cost of manufacture. One convenient and inexpensive way 100 to make the pocket or seal-holder 6 is to stamp it from sheet metal and then bend or press a portion of the bottom wall of 105 110

said pocket downwardly so as to form a lip or substantially U-shaped member 4 that is adapted to receive the hook 5 on the upper end of the movable element 2 of the locking device.

The seal C is slipped into the holder or pocket 6 when the lid A of the box is raised, and when said lid is moved downwardly so as to close the box the front edge of the member 4 on the under side of the lid strikes against the downwardly inclined hook 5 on the upper end of the member 2 and thus forces the member 2 outwardly or toward the front wall B of the box. As soon as the front edge of the member 4 moves out of engagement with the hook 5, the member 2 will spring back to normal position, moving the hook 5 over the member 4 and thus securely locking the lid of the box in its closed position, as shown in Fig. 1.

To open the box, the operator inserts his finger through the opening 1 in the lid so as to break the seal C and thus permit the finger to pass into the box far enough to engage the member 2 and move it forwardly or toward the front wall B of the box far enough to carry the hook 5 and the upper end of same out of engagement with the member 4 on the under side of the lid. As soon as the movable member 2 of the device has been disengaged from the co-operating stationary member 4 on the under side of the lid the lid can be raised. As shown in Figs. 1 and 2, the rear side of the member 5 is curved at 4^a so that said member will conform approximately to the shape of the operator's finger and thus form a member that is easy to grasp during the operation of raising the lid.

40 A box fastener or lid-locking device of the construction above-described is inexpensive to manufacture and install because it comprises only three parts, namely, the resilient member 2 that is secured to the inner side of the front wall of the box and which

may be conveniently formed from a strip of spring metal, the seal-holder that is secured to the under side of the lid and which is provided with an integral portion that cooperates with said resilient member, and the seal that is arranged in said holder. It would be impossible to release the device and raise the lid without first breaking the seal because the holder or pocket in which the seal is arranged is so designed that the seal 55 cannot be shifted or moved out of alignment with the opening in the lid. And still another desirable feature of such a box fastener is that the act of breaking the seal, disengaging the movable element, and grasping the lid, is effected by a single operation, namely, inserting the finger through the opening 1 in the lid far enough to break the seal C and push the member 2 forwardly out of engagement with the co-operating member 60 4 on the under side of the lid.

Having thus described my invention, what I claim as new and desire to secure by Letters Patent is:

A box fastener comprising a seal-holder 70 arranged on the under side of the lid of the box in proximity to an opening in said lid and stamped from a piece of metal that is bent so as to form a pocket, a substantially U-shaped member at the front of said pocket, 75 and flanges through which fastening devices pass to secure the holder to the lid, and a resilient member on the inner side of the front wall of the box provided at its upper end with a hook that projects into the U-shaped 80 member on said holder when the lid is closed.

In testimony whereof I hereunto affix my signature in the presence of two witnesses, this first day of May 1912.

ERNEST W. STAMM.

OTTO GAFFRON.

Copies of this patent may be obtained for five cents each, by addressing the "Commissioner of Patents, Washington, D. C."

Correction in Letters Patent No. 1,080,859.

It is hereby certified that in Letters Patent No. 1,080,859, granted December 9, 1913, upon the application of Ernest W. Stamm, of St. Louis, Missouri, for an improvement in "Box-Fasteners," errors appear in the printed specification requiring correction as follows: Page 1, line 102, and page 2, lines 10, 15, 18, 29, 32, and 66, for the reference-numeral "4" read 5; and page 2, lines 3, 11, 18, and 27, for the reference-numeral "5" read 4; and that the proper corrections have been made in the files and records of the office and are hereby made in said Letters Patent.

Signed and sealed this 30th day of December, A. D., 1913.

[SEAL.]

J. T. NEWTON,

Acting Commissioner of Patents.
